ELECTRICAL INDICATING INSTRUMENT

Louis W. Parker, 375 Fairfield Ave., Stamford, Conn.

Filed Sept. 29, 1960, Ser. No. 62,308

Term of patent 14 years

(Cl. D52—6)

FIG. 1.

FIG. 2.

FIG. 3.

FIGURE 1 is a front view of an electrical indicating instrument, showing my new design;

FIGURE 2 is a side elevational view; and

FIGURE 3 is a bottom end view thereof.

The dominant features of my new design are shown in solid lines in the drawing.

I claim:

The ornamental design for an electrical indicating instrument, substantially as shown and described.
